UNITED STATES PATENT OFFICE.

CHRISTOPHER C. HAZLETT AND WILLIAM A. RICH, OF ASHLAND, OHIO.

CAR-COUPING.

SPECIFICATION forming part of Letters Patent No. 686,518, dated November 12, 1901.

Application filed December 20, 1900. Serial No. 40,539. (No model.)

To all whom it may concern:

Be it known that we, CHRISTOPHER C. HAZLETT and WILLIAM A. RICH, citizens of the United States of America, residing at Ashland, in the county of Ashland and State of Ohio, have invented certain new and useful Improvements in Car-Couplers, of which the following is a specification, reference being had therein to the accompanying drawings.

10 This invention relates to certain new and useful improvements in car-couplers, the object being to provide improved means for automatically throwing the knuckle outward when released from its locking means.

15 The present invention relates more particularly to a car-coupler of the Janney type.

The invention has for its object to construct a device of this class that will be extremely simple, strong, durable, and highly efficient 20 in its operation.

With the above and other objects in view the invention consists in the novel combination and arrangement of parts, to be herein-after more fully described, and specifically 25 pointed out in the claims.

30 In describing the invention in detail reference is had to the accompanying drawings, forming a part of this specification, and wherein like numerals of reference indicate corresponding parts throughout the several views, in which—

Figure 1 is a perspective view of the draw-head, having our improvements attached thereto. Fig. 2 is a vertical sectional view 35 thereof. Fig. 3 is an enlarged vertical sectional view of the upper portion of the lug and pin. Fig. 4 is an enlarged end view of the pivot-pin.

In the drawings the reference-numeral 1 indicates the draw-head, and 2 the knuckle thereof, the latter being rotatably mounted in the lugs 3 and 4, formed integral with the draw-head. The lug 3 has formed on its upper face ratchet-teeth 5, extending radially 40 upon said face.

45 The reference-numeral 6 represents a pin extending through the lugs 3 and 4 and through the knuckle 2, said pin carrying at its upper extremity a head 7, which carries ratchet-

teeth 8 on its under face, said ratchet-teeth 8 50 registering with the ratchet-teeth 5 of the lug 3. The lower extremity of the said pin 6 has formed therein a slot 9 to receive a key-wedge 10, to which is secured a helical spring 11, which is adapted to encircle the lower end 55 of the pin 6, the other end of said spiral spring being attached at 12 to the under face of the knuckle. The helical spring is so constructed and arranged as to normally retain the knuckle outwardly, said spring also having a downward pressure against the key-wedge, which will tend to engage the ratchet-teeth of the head with the ratchet-teeth of the lug and tend to lock the same.

Upon the uncoupling of the cars the tension 65 of the spring 11 will serve to withdraw the knuckle from the draw-head and to maintain the same in this position, so that the cars may be again readily coupled when brought together.

The many advantages obtained by the use of our improvements will be readily apparent, and it is thought a further detail description as to the operation of the device is unnecessary.

It will be noted that various changes may be made in the details of construction without departing from the general spirit of our invention.

Having thus fully described our invention, 80 what we claim as new, and desire to secure by Letters Patent, is—

1. In a car-coupler, the combination with a draw-head, a pin secured in said draw-head carrying at its upper extremity a head, ratchet-teeth secured to the under face of said head, ratchet-teeth arranged upon said draw-head engaging the ratchet-teeth of the head, a knuckle mounted upon said pin, and a helical spring encircling the lower portion of said 85 pin with its one end engaging in the knuckle and its other end connected to the pin, substantially as described.

2. In a car-coupler, the combination with a draw-head, a pin secured in said draw-head carrying at its upper extremity a head, ratchet-teeth formed on the under face of said head, ratchet-teeth arranged upon said draw-head 90

engaging the ratchet-teeth of the head, a knuckle mounted upon said pin, a key-wedge secured in the lower end of said pin, and a helical spring encircling the pin between the 5 wedge and the draw-head, said spring having its one end connected to the knuckle and its other end connected to the key-wedge carried by the pin, substantially as described.

In testimony whereof we affix our signatures in the presence of two witnesses.

CHRISTOPHER C. HAZLETT.
WILLIAM A. RICH.
